UNITED STATES PATENT OFFICE

2,526,368

FLOWER STEM WINDING MACHINE

Ernest G. Keller, North Bergen, N. J.

Application June 14, 1946, Serial No. 676,709

2 Claims. (Cl. 57—15)

1

This invention relates to improvements in flower stem winding machines.

One of the objects of this invention is to produce a highly efficient stem-winding machine that will combine with a wrapping or winding head a variable-speed feed mechanism for feeding a trunk stem of artificial flowers through said head at a speed synchronized with the speed of rotation of the winding head to enable a simultaneously wrapping or covering of said trunk stem with a tape or tapes of paper or like material and the fastening thereto of subsidiary stems of flowers, while controlling the layering of the tape and providing an even spiraling pitch thereof that will fix the width of the exposed and lapped portions of the wrapping tapes.

Another object of my invention is the provision, in a machine of the type specified, of means for manually adjusting the speed of the variable-speed mechanism to permit ready and easy synchronization and conformance thereof to the speed of rotation of the head and of varying diameters of trunk stems.

Another object of my invention is the provision, in a machine of the character specified, of tape-guiding means preferably comprising tapered guide rolls for applying the tape onto the trunk stem in a spiral path and for causing the tape to be guided around the axis of the trunk stem on a proper bias in relation to the edges of the tape, and thus to procure an even, tight and smooth wrapping or layering of the tape on the surface of the trunk stem at a suitable pitch.

Still another object of my invention is, in a machine of the type specified, to provide means whereby the entire length of the trunk stem may be projected through the winding head and through the winding area adjacent thereto so as to enable even and smooth winding or wrapping of the entire surface thereof.

Still another object of my invention is, in a machine of the character specified, to combine a tape-winding head and means for actuating the same at a fixed speed of rotation with a stem-propulsion means having an operative connection with a speed-varying gearing in order to produce a suitable synchronization and a predetermined layering and winding pitch of a tape-material on a stem, and also to provide means for manually adjusting said speed of said speed-variable gearing in relation to said fixed speed of rotation in order to conform and synchronize said speeds to trunk stems of varying diameters being covered or wrapped.

Still another object of my invention is, in a machine of the type specified, to utilize a manu-

2

ally operable element having a screw-adjustment for adjusting the speed of the trunk-stem propelling mechanism to synchronize the same with the speed of rotation of the winding head.

5 Another object of my invention is to utilize mechanism by which a plurality of strips of paper-tape may be applied simultaneously to cover a single stem, to fasten thereto branch stems and to centralize trunk stems during tight winding.

10 With these and other objects in view, the invention comprises the combination of members and arrangement of parts so combined as to contact and cooperate with each other in the performance of the functions and the accomplishment of the results herein contemplated, and comprises in one of its adaptations the species or preferred form illustrated in the accompanying drawings, in which:

Fig. 1 is a view in side elevation of a motor-driven machine embodying my invention including a propelling mechanism and a winding head;

Fig. 2 is an enlarged view in side elevation of the propelling mechanism and winding head shown in Fig. 1;

25 Fig. 3 is a similarly enlarged view in plan of the propelling mechanism and head shown in Fig. 2;

Fig. 4 is a similarly enlarged view in front elevation of the mechanism shown in Figs. 2 and 3;

30 Fig. 5 is a similarly enlarged central vertical section of the propelling mechanism and head shown in Figs. 1 to 4 inclusive;

Fig. 6 is an enlarged fragmentary section on the line 5—5 of Fig. 3 of the tape-feeding guide-means of the head;

35 Fig. 7 is an enlarged fragmentary section of my preferred connection between a trunk-stem and an extension rod to enable projection of the rear end of the trunk-stem beyond the winding head;

Fig. 8 is a cross-section on the line 8—8 of Fig. 2 looking in the direction of the arrows;

Fig. 9 is a fragmentary section on the line 9—9 of Fig. 2 looking in the direction of the arrows;

40 Fig. 10 is a view in side elevation similar to Fig. 1 of a modified form of mechanism to support the rear end of a trunk-stem during wrapping;

Fig. 11 is a cross-section taken at the forward edge of the tape-spools and through a paste-applying mechanism shown in Fig. 10;

Fig. 12 is a section on the line 12—12 of Fig. 10 looking in the direction of the arrows;

Fig. 13 is a section on the line 13—13 of Fig. 10 looking in the direction of the arrows;

Fig. 14 is a section similar to Fig. 5 showing

a modified and preferred form of paste-applying mechanism; and

Fig. 15 is a section on the line 15—15 of Fig. 14 looking in the direction of the arrows.

Referring now to these drawings, which illustrate a preferred embodiment of my invention, A indicates a mounting platform or table on the upper surface of which I mount my winding head and trunk-stem propelling mechanism. Said propelling and winding mechanism are driven by an electric motor M mounted, as shown, on a bracket B fixed on the under-surface of the platform A and operatively connected by suitable power-transmission mechanism P for supplying power to a power shaft S which, through drive pulley 18 fixed thereon and belt 11, transmits power to driven pulley 12 fixed on hollow drum 17 through which power is supplied for actuating said head and propelling mechanism.

In the embodiment of my invention shown, I mount on the table or platform a base member 13 provided with a bearing 14 in which the hollow drum 17 is rotated by the pulley 12. A pulley 15 is also, as shown, fixedly connected with said pulley 12 and hollow drum 17 and transmits power through an intervening variable-speed device or gear 18 to a trunk-stem propelling mechanism 16 including a knurled propelling roller 33. As illustrated, the pulley 15 is provided with a belt 19 which rotates a variable-speed pulley 20 provided with a conventional variable-speed mechanism 20a. Pulley 20 is mounted on and adapted to rotate a shaft 21, which in turn rotates a pulley 22 connected by belt 23 with a pulley 24, also provided with conventional variable-speed mechanism 24a. Pulley 24 in turn actuates a shaft 25 connected with a worm gear mounted in a gear box 25a and comprising a worm shaft 26 and worm wheel 27. The worm wheel 27 of said worm gear is mounted on and rotates a shaft 28 mounted in bearing 14a and having fixed thereon a gear wheel 29 meshing with a gear wheel 30 mounted on a shaft 31 which rotates the knurled roller 33. The roller 33 and shaft 31 are supported in one arm 32a of a crank 32 pivoted on the shaft 28, the other arm 32b of said crank being connected by link 34 with a pressure crank-arm 35 pivoted at 35a to a projecting bearing 14b and having mounted therein a pressure roller 36 adapted to register with the knurled roller 33. The cranks and links thus described provide for a relative separating movement of the rollers 33 and 36, and in lowered position the crank 35 is arranged to cause pressure to be applied by said rollers 33 and 36 against a trunk-stem TS being propelled through the machine by the knurled roller 33.

The handle 37 connected to the crank arm 35 is adapted to permit manual separation of the rollers 33 and 36 and particularly to lift the roller 36 away from and to free the roller 33.

Suitable means for guiding the trunk stem TS axially through the machine is preferably provided and, as illustrated, a hollow pipe 38 is adjustably mounted in a chuck 39 and projects forwardly therefrom into a position adjacent to the rollers 33 and 36. As shown, the chuck 39 is mounted on a rod 40 adjustable by a split collar 41 arranged at the end of a shelf arm 42 which is also adjustably mounted on a stand 43 supported on a base 43a and preferably having suitably mounted at its upper end a grooved roller 44 which is adapted to support a trunk-stem TS or its extension member hereinafter specified. I also preferably provide at the opposite or forward

side of the rollers 33 and 36 a hollow tube or pipe 45 which extends to a position close to the outer end of the drum 17 and in adjacency with the winding mechanism of a winding head 46 supported upon and rotated by said drum. As illustrated, the guide tube or pipe 45 is mounted and supported at its forward end in an axially-disposed collar 47 which is in turn supported by a disc 48 extending and connected to the drum 17 by set screws 48a.

The winding head 46 comprises a face plate or disc 49 provided with a central opening 50 for the passage therethrough of the trunk stem TS and having surrounding said opening 50 a series of tape-guide members hereinafter more particularly described. The winding head 46 and its face plate 49 is rotated from the drum 17 and, as shown, said face plate is mounted and securely fastened to the outer ends of spaced arms 51 projecting outwardly parallel with the path of movement of the stem TS and with the axis of the tube 45. As illustrated, pairs of such spaced arms 51 are mounted to project from the face 12a of the pulley 12, and are suitably fastened thereto and rotate therewith.

In the instant machine, these arms are arranged in pairs and the plate or disc 49 abuts the ends and is securely fastened thereto.

A bushing 12b is applied between the bearing 30 sleeve 14a which is fastened to the bearing 14 to form a hub on which the bushing 12b is mounted and on which the pulleys 12 and 15 rotate.

Each pair of the arms 51 have supported thereon a spool 53 of paper-tape PT. The spools are 35 rotatably supported on brackets 52 and the paper tape, in the embodiment shown, passes through oppositely positioned radial slots 54 in the face plate 49 and thence is guided as more particularly shown in Fig. 4 over guide fingers 55 mounted adjacent to said slots, thence the tapes are led in opposite directions around a pair of erecting spools 56, thence over another pair of similar spools 57, thence over a pair of adjustable tensioning members 58 preferably comprising 45 knurled tape-tensioning rollers tensioned by a suitable coiled spring and finally are led over a pair of inwardly-tapered guide members 60 which guide the paper tape on to the surface of the trunk-stem and apply the tape thereto in a spiral path at a suitable bias in relation to the edges of the tape and at an angle to the axis of the stem, and also will cause the tape to be guided around the trunk-stem at such bias as to produce a suitable pitch of spiralling to provide a proper width 55 of exposed wrapper and a suitable overlap and also to produce an even, tight and smooth wrapping or layering of the tape on the surface of the trunk-stem at such pitch.

In operation of the machine described, I 60 preferably provide pedal mechanism for stopping and starting the machine and, as illustrated, I provide a braking clutch member 61 which is connected to a treadle rod 62 but normally holds the machine through spring 63 in operative condition, but upon depression of the rod 62 permits the machine to be started and continued running so long as said rod is depressed but will be immediately stopped when the operator takes his or her foot off a suitable treadle.

An important feature of my invention provides for manually varying the speed of the speed-variable gearing hereinabove specified, and to this end, I mount two of the pulleys of my variable-speed gearing on one arm of a pivoted crank and provide means for adjustably moving the opposite

arm of said crank to vary the diameter of the pulleys of said variable-speed gearing. As shown, a pivot 65 is supported in bearings 66 on the base 13, a two-armed crank member 67 is pivotally mounted on said pivot. I provide on one arm 67^a of said pivoted crank bearings 68 for the shaft 21 of the wheels 20 and 22 of said variable speed gearing and the opposite arm 67^b of said pivoted crank is provided with an adjusting-screw device comprising a screw-threaded member 69 having its threads meshing with an internal thread in a nut portion 70 near the end of the crank arm, said screw being provided at its top end with a handle 71 to permit movement thereof against the metal base plate 13 of the machine to adjustably move the opposite arm 67^b outward or inward about the pivot 65 and thus to cause the embedding of the belts in the grooves of said wheels 20 and 22 and the changing or variation of the diameters thereof, so as to vary the speed of the variable speed gear and consequently to vary the propulsion of the trunk-stem.

Under certain conditions, it is desirable to apply glue to the trunk-stem prior to the application of the paper-tape and I have, therefore, shown embodied in my machine a paste pot 72 which, as more particularly shown in Figs. 5 and 11, comprises an annular container 73 having an internal bore 74 provided with a cylindrical wall arranged concentrically with the trunk-stem TS and being provided with dispensing nozzle 75 in which is seated a brush or wick 76 adapted to carry paste from the annular container 73 to the said trunk-stem TS. As illustrated, said container is provided with attaching brackets 77 mounted on the shank portions of two diagonally disposed arms 51. The operation of this paste device will be obvious.

It is necessary that the trunk-stem be moved through the machine after the end thereof leaves the propulsion rollers, and in Figs. 5 and 7 I have shown my preferred method which comprises means for pushing the rear end of the trunk-stem through the machine and beyond the tape-apply area at the front of the head. In the construction illustrated in these figures, I provide a tube 78 of substantially similar diameter to the trunk-stem TS. One end of this tube is provided with an internal thread 79 and the rear end of the trunk-stem, which is preferably of softer material than the extension tube 78, will be screwed into the end of the tube. The internal screw threads 79 will thus bite into the end of said tube so as to form a secure connection therewith. The tube so fastened is fed through the propulsion rollers and obviously, the tube 78 should be of a length somewhat longer than the distance between the propelling rollers and the winding head of the machine so that the rear end of the trunk-stem will be pushed thereby through the machine. When the end of the trunk-stem passes beyond the winding head, the tube may be turned to release the connected portion which may be covered or wound with tape.

In Figs. 10 and 13, I have shown a modified means of providing for the movement of a trunk-stem TS completely through the machine. Thus, in Fig. 10 I have mounted at the forward side of the head a power-rotated pulling roller 80 and a pressure roller 89 in contact therewith. These rollers are adapted to engage the projected forward end of the stem TS and to guide and pull the stem through the head after the opposite end thereof leaves the propelling rollers 32-36.

In this construction, the roller 80 is driven through the shaft 28 that controls the rotation of the propelling roller 33 so that said rollers 80 and 33 will be synchronized. As shown, the roller 80 is mounted on a stub-shaft 81 supported in one arm 82^a of a crank lever 82 and rotated by a gear wheel 83 which meshes with another gear 84 on a shaft 85 mounted in a bearing 86^a in the standard 86. The other arm 82^b of the crank 82 is provided with means for adjusting the position of the crank 82 so as to provide suitable pressure on the roller 80, and, as illustrated, this arm 82^b is provided with a slot 86 which is engageable with a fixed screw 87 on the standard. At the top of the standard I also preferably pivot on pivot 88^a a hand-operated lever 88 provided with a pressure roller 89 mounted in a forked downwardly projecting bearing 89^a registering with the roller 80 and adapted to engage the upper surface of the trunk-stem TS in cooperation with said roller 80. This lever 88 is preferably held in position to cause roller 80 to so engage the stem TS by an expansion spring 90 stretched between the shank of the lever 88 and the standard. The lever 88 is also preferably provided with a handle 91 adapted to permit manual swinging of the roller upwardly out of the way and to free the roller 80 so as to permit the manual disengagement of the stem TS from both rollers 80 and 89 after the wrapping is concluded. The gear 84 is preferably operated through a chain 92 from a gear 93, and in this construction the propelling mechanisms at the rear of the machine and at the forward part of the machine are synchronously driven by connecting sprocket 93 through chain 94, sprocket 95 and chain 96 with a sprocket 97 fast on the shaft 28 through which the propelling roller 33 is driven. The winding head, variable-speed pulleys and other mechanism in this embodiment are in all respects substantially similar to that hereinabove described.

Referring now to Figs. 14 and 15 of the drawings, I have shown my preferred form of mechanism for applying paste to a trunk-stem TS before the winding of tape thereon. In these figures, a head-plate-disc 48^a has a perimetric flange adapted to fit over the forward edge of the hollow bearing or axle 14^a and, as shown, the disc is held in place and is removably fastened or secured to the hollow axle 14^a by a set screw 48^b and forms a mounting member for the paste-applying mechanism hereinafter specified. Said mounting disc or head plate 48^a, in the embodiment shown, has fixedly mounted thereon a paste receptacle 98 provided with a rotatably-mounted paste-transfer roller or wheel 99 which, as shown, is provided with flanges 101 and dips into a body of paste P in the receptacle 98. By frictional contact with the stem, the roller 99 rotates to transmit paste P to the trunk-stem TS. In the embodiment shown, the mounting disc 48^a is provided with a central or axial opening 48^c through which the guide tube 45 extends. The trunk-stem TS, when the machine is operated, passes through this tube and rides upon the flanges 101 of the transfer roller 99. As illustrated, the roller 99 is rotatably mounted in the receptacle and for this purpose is provided with axles 100 adapted to fit into bearing slots 102 in the side edges of the receptacle 98. The roller 99 is thus, when properly adjusted, adapted to contact with the trunk-stem and to be rotated thereby. The flanges form a V-shaped groove in the peripheral surface of the roller

and in view of the position of the trunk-stem in said groove between or within the flanges 101, it will be, upon rotation of the transfer roller, coated with paste, any excess of which may be removed in conventional manner.

The receptacle 98 is, as shown, fixedly mounted upon a U-shaped fastening plate 103 provided with upwardly extending flat forks 103^a each of which has a slot 104 adapted to extend beneath set screws 105 engaged in the disc 48¹ and having knurled knobs so as to enable manual adjustment of the fastening plate in relation to the disc 48¹. While the flanges 101 and the V-shaped groove formed thereby permit the feeding of paste to stems of varying diameters within certain limits, the aforesaid adjustability enables adjustable movement of the receptacle 98 for the purpose of inserting feeding or transfer rollers 99 of larger or smaller diameters when it is desired to feed paste to stems of diameters beyond the capacity of said flanged-groove.

The operation of this paste-applying mechanism will be obvious from the above description, and it will also be obvious that the movement of the trunk-stem will cause the roller 99 to rotate and thus to transfer paste P from the receptacle to a trunk-stem before the same is wound with tape.

Having described my invention, I claim:

1. A flower stem-winding machine embodying, in combination, a winding head rotatable about a horizontal axis and having a face plate extending perpendicular to said axis, means for feeding tape to said head, power means for rotating said head, propelling members for feeding a stem to be wrapped through said head, means for transmitting power from said head-rotating power means to said propelling members, and a tape-guiding roller member mounted on said winding head to revolve with said head and also to rotate independently about an axis perpendicular to said face plate, said roller having an inwardly-tapering conical guiding surface for applying the tape onto the stem in a spiral path and for causing the tape to be

guided around the axis of the stem in suitable relationship to the edges of the tape, and thus to procure an even, tight and smooth wrapping or layering of the tape on the surface of the stem at a suitable pitch.

2. A flower stem-winding machine embodying, in combination, a winding head rotatable about a horizontal axis and having a face plate extending perpendicular to said axis, means for feeding tape to said head, power means for rotating said head, propelling members for feeding a stem to be wrapped through said head, means for transmitting power from said head-rotating power means to said propelling members, and a plurality of tape-guiding roller members each mounted on said winding head to revolve with said head and also to rotate independently about an axis perpendicular to said face plate, each roller having an inwardly-tapering conical guiding surface for applying the tape onto the stem in a spiral path and for causing a plurality of layers of tapes to be guided around the axis of the stem in suitable relationship to the edges of the tape, and thus to procure an even, tight and smooth wrapping or layering of the tape on the surface of the stem at a suitable pitch.

ERNEST G. KELLER.
